UNITED STATES PATENT OFFICE.

FRANK M. BUDLONG, OF SAN JOSE, CALIFORNIA, ASSIGNOR OF THREE-FOURTHS TO
WILBUR F. BUDLONG, OF BEREAL, OHIO.

AUTOMATIC-BALANCE HIGH-PRESSURE PUMP.

1,004,982.

Specification of Letters Patent.

Patented Oct. 3, 1911.

Application filed March 20, 1911. Serial No. 615,750.

To all whom it may concern:

Be it known that I, FRANK M. BUDLONG, a citizen of the United States, residing at San Jose, in the county of Santa Clara and 5 State of California, have invented certain new and useful Improvements in Automatic-Balance High-Pressure Pumps, of which the following is a specification.

This invention has reference to an automatic balanced high pressure pump and storage tank adapted, among other uses, to be advantageously employed for spraying trees, all substantially as shown and described and particularly pointed out in the 15 claims.

In the single figure of illustration of the invention forming a part of this specification, there is shown a vertical sectional elevation of the complete device or apparatus 20 and which comprises a liquid storage or pressure tank T having an outlet 2 at its bottom with which a pipe or hose can be connected for any purpose according to the use that is made of the device for the time 25 being. Along with this tank I provide means for forcing liquid into the same against accumulating atmospheric pressure therein, and have so constructed the parts that the said pressure can be utilized to assist 30 in the hand operation of the liquid pump and balance the pressure. Thus, C represents a pump or pump cylinder and P a piston or plunger therein having to do with forcing the liquid into tank T. The 35 said cylinder is shown as supported upon a base B of cast metal, in this instance, and having liquid channels therein with an intake through pipe E and running first to the base of the pump and thence past the 40 two check valves V and V' to the tank T. Said valves are located in especially constructed cages or cribs indicated by 3 and 4 respectively and located one directly over the other and in this instance constituted of 45 separate parts set into the main casing or base B. Each cage has its ball valve, above noted, adapted to seat by gravity and to open successively under the action of the pump. Entrance of the liquid as it passes 50 valve V' is by short pipe or coupling 5.

M. represents a motor cylinder located in line with pump cylinder C above and apart therefrom and supported from base B on rods or uprights 6. A piston N in cylinder 55 M is connected with piston or plunger P by

a rod or bar R, and said parts together are adapted to be reciprocated by means of hand operating lever L. This lever is pivoted on base B at 7 and has a crank arm 8 extending inward to a point substantially in line with 60 piston rod R with which it is connected by link or links 9 and a trunnion or trunnions 10 about midway lengthwise on said rod and at a point above cylinder C relatively 65 about as shown. The lever L has a swing- 70 ing back and forth movement on its pivot 7 and both the pump and the motor are operated simultaneously thereby. The first essential of this operation of course is the forcing of the indrawn liquid into tank or 75 receptacle T past the check valves V and V', and incident to this and as an auxiliary agency or force we have the action of the compressed air upon the pneumatic motor. The said motor is connected with the top or 80 dome of tank T by means of a pipe line G, in which are two shut-off valves g and g', the valve g controlling the flow in pipe G between the pump and the tank, and valve g' serving as a flow-off or open vent valve 85 as operations may require. For example, if for any reason, the valve g should be closed the valve g' could be opened and the said motor would run idle while the liquid pump is at work. Otherwise, with valve g' closed 90 and valve g open in operation any accumulated pressure of air in the top of the tank by reason of filling in of liquid from beneath would react on piston N and thus assist in depressing the plunger P and in a 95 measure balance or equalize the downward action with the upward action of said plunger. Thus a more or less uniform resistance is established which the operator has to deal with through lever L and cer- 100 tain compensations of pressure are obtained especially when otherwise the down stroke of the liquid pump would be hardest. Obviously the ultimate object of all the above mechanism is to create and maintain a sustained atmospheric pressure in tank T with a quantity of liquid therein so as to force a uniform stream of liquid from the bottom of the tank to the spraying device, not shown, but which may have connection with 105 opening 2. The pressure of air on the piston N from expansion of the whole volume of compressed air in tank or chamber T is available to assist the operator in discharging the liquid from the pump at a higher 110

pressure than would be possible without such assistance.

In the operation of a pump of the type shown the operator stands erect facing the pump. The greater force could be applied to the handle by the forward movement of the handle causing downward or pressure movement of the liquid piston. The ratio of the area of the pistons would therefore 10 vary from any fixed constant according to the height, weight or strength of the operator. By actual practice it is found that this variation as to the application of the operating power is slight, and that the average person can, with convenience, apply twice the power on a forward or downward movement as compared with a reverse movement by reason of the added weight of the trunk of the operator together with the natural training of the muscles of the body and limbs to forward movements. Therefore I establish the ratio of the cylinders, theoretically, to the ratio of the ease of the average operator in the expenditure of power in 20 order to equalize the labor.

For the convenience of operators other than average, and in order to provide proper equalization of energy expended by such operators the valve *g* can be slightly closed or 30 fully opened to permit checking of the air flowing from the cylinder to the chamber *M* and the reverse or the freer flow as the case may be to give a delicate and actual equalization for all operators according to their 35 fancy.

What I claim is:

1. In a pump and liquid storage mechanism, a tank adapted to receive liquid under pressure, a manually controlled pump outside said tank adapted to force liquid into the tank and a motor under pressure from the tank operatively connected with said pump and adapted to assist in the operations of the pump.

45 2. A tank and a pump outside thereof and a fluid passage connecting said parts and

provided with a plurality of valves, in combination with an auxiliary power mechanism adapted to utilize the atmospheric pressure in the tank to lighten the operations of the pump and comprising a separate chamber and a piston therein mechanically connected with said pump.

3. A tank and pump mechanism adapted to force liquid into the same, a hand lever to operate the pump and a separate pneumatic motor having a chamber open to the tank and a piston therein connected to the pump.

4. A fluid storage tank and a pump arranged to force fluid into the same under pressure, in combination with a pneumatic motor having air connection leading to said tank and provided with an operating connection united with said pump, and a device to operate said pump and motor simultaneously, whereby when the pump is forcing fluid into the tank the air under pressure is utilized by the motor to lighten the operations of said operating device.

5. A tank adapted to receive fluid under pressure, a pump having a piston to force the fluid into the tank and a valved connection uniting said tank and pump, in combination with a pneumatic motor having open communication with the tank and provided with a piston of lesser piston area than the pump piston, and a power device to reciprocate both pistons simultaneously.

6. A liquid storage tank and a pump outside the tank arranged to force liquid into the same, a motor having valve controlled pressure connections with the top of said tank and operatively connected with said pump and a hand lever to operate the pump.

In testimony whereof I affix my signature in the presence of two witnesses.

FRANK M. BUDLONG.
